ARTICLEByron E. Freitag, Fort Wayne, Ind., assignor to
General Electric Company, a corporation of
New York

Application December 30, 1948, Serial No. 150,437

Term of patent 14 years

(Cl. D67—4)

To all whom it may concern:

Be it known that I, Byron E. Freitag, a citizen of the United States, residing at Fort Wayne, in the county of Allen, State of Indiana, have invented a new, original, and ornamental Design for a Cabinet for a Bottled Beverage Cooling Unit or Similar Article, of which the following is a specification, reference being had to the accompanying drawing, forming a part thereof.

The single figure of the drawing is a perspective view of a cabinet for a bottled beverage cooling unit or similar article embodying my new design. The other end wall of the cabinet is like that shown.

I claim:

The ornamental design for a cabinet for a bottled beverage cooling unit or similar article, substantially as shown and described.

BYRON E. FREITAG.
